(57) **CLAIM**

The ornamental design for a “seat belt cell phone caddy”, as shown and described.

DESCRIPTION

FIG. 1 is a perspective view of a seat belt cell phone caddy, showing my new design;

FIG. 2 is a front elevational view thereof;

FIG. 3 is a rear elevational view thereof;

FIG. 4 is a left side elevational view thereof;

FIG. 5 is the right side elevational view thereof;

FIG. 6 is a top plan view thereof; and,

FIG. 7 is a bottom plan view thereof.

The broken line showing of a cell phone and seat belt is for illustrative purposes only and forms no part of the claimed design.
